CLAIM

The ornamental design for a measuring rule, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of a measuring rule;

FIG. 2 is a top plan view thereof; and,

FIG. 3 is a top plan view thereof.

Portions of the measuring rule in FIGS. 2 and 3 have been omitted for ease of illustration.

1 Claim, 2 Drawing Sheets**(2 of 2 Drawing Sheet(s) Filed in Color)**(56)
